UNITED STATES PATENT OFFICE.

HENRY CLAY RONEY, OF PRINCETON, WEST VIRGINIA.

THROTTLE VALVE.

1,409,783.

Specification of Letters Patent. Patented Mar. 14, 1922.

Application filed November 10, 1920. Serial No. 423,097.

To all whom it may concern:

Be it known that I, HENRY CLAY RONEY, a citizen of the United States, residing in Princeton, in the county of Mercer and State 5 of West Virginia, have invented certain new and useful Improvements in Throttle Valves, of which the following is a specification.

This invention relates to locomotive throttle valves of the kind used in the steam dome 10 to control the passage of steam from the boiler to the steam chests which supply the steam engines of the locomotive. Throttle valves of this class are commonly located in a casing or box known as a "throttle box" 15 which is detachably connected with the upper end of a stand pipe which in turn connects with the "dry pipe" through which steam is conveyed to the engine cylinders. The throttle box is formed with a valve seat 20 or valve seats and the valve is raised and lowered by rods and levers actuated by suitable devices in the locomotive cab.

The steam dome is provided with a removable cap or cover which when withdrawn 25 affords access to the valve mechanism for cleaning purposes or for repair. Heretofore, however, the valve operating mechanism has been so mounted and arranged that it has been necessary to disconnect it from 30 the body of the dome and to remove the valve and the valve box whenever it is desired to enter the boiler or to inspect the boiler or the interior of the dome.

According to my invention the throttle 35 valve is supported by the stand pipe, which latter is supported by a bracket secured to the boiler on one side of the opening through which the stand pipe extends into the dome. The throttle box can be readily and quickly 40 removed from the dome by disconnecting it from the stand pipe whenever desired. The valve and the valve box are so constructed that the boiler can be inspected without removing any part of the throttle valve or operating mechanism from the dome. In order 45 to grind the throttle valve it is only necessary to remove the dome cap and one bolt that connects the valve operating arm with the valve, when the valve can be removed from the dome.

One of the main features of this invention is a pilot valve or drift valve of improved construction which can be so operated as to admit a limited quantity of steam from the 50 dome to the stand pipe before the main

throttle valve is raised or without raising the throttle valve.

Other features of the invention will be hereinafter described.

In the accompanying drawings which 60 show the preferred form of my invention:

Figure 1 is a view partly in plan and partly in section and with parts broken away showing how my improvements are applied in the steam dome of a locomotive. 65

Figure 2 shows a vertical section on the line 2—2 of Figure 1.

Figure 3 shows a similar section on the line 3—3 of Figure 1.

Fig. 3^a is a sectional view of the throttle 70 valve and the drift valve showing the vertical grooves in the central bore of the throttle valve.

The steam dome A is connected with the locomotive boiler B in the usual way. a indicates the upper part of the dome which is 75 permanently connected with the lower part as shown. The dome cap a' is removably connected with the upper part of the dome by fastening devices a² of any preferred 80 form. By removing the dome cap, the interior of the dome and the boiler may be reached without the removal of other parts. C indicates the dry pipe leading to the steam chests and D, the stand pipe which connects 85 the dry pipe with the throttle box. D' indicates a bracket attached at d³ to the boiler shell at one side of the opening d' and which is so connected with the stand pipe as to assist in supporting it. 90

The upper end of the stand pipe is formed with a flange d to which is bolted the lower flanged end e of the valve box E. A cylindrical extension e' from the lower portion of the valve box projects into the stand pipe, 95 forming a joint therewith, and the lower portion of the valve box is provided with a valve seat x. A valve seat y is formed at the upper end of the valve box and another valve seat z is formed in the box intermediate its upper and lower ends. e² indicates ports in the side of the valve box through which steam passes from the dome to the interior of the box. It will be observed that there are a number of these ports arranged 100 around the valve box in such manner as to freely admit steam from the dome to the box. 105

The valve G has an upper portion g adapted to seat on the box at y, a middle portion 110

g' which seats on the box at *z*, and a lower part *g*² which seats at *w*. It will be observed that steam normally exerts pressure on the outside of the upper part of the valve 5 and also on the under side thereof, thus partially balancing the valve. The valve G has a central bore *h* through which extends a pilot valve rod H which has a seat in the top of the valve G at *h'*. The rod 10 H extends through the bore *h* and carries at its lower end a nut *h*². The rod H is slightly smaller in diameter than the bore *h* and operates freely therein, but when the valve is lowered the passage of steam through 15 the bore of the throttle valve is prevented. Vertical grooves or channels *w* are formed in the walls of the bore *h* of the throttle valve and these grooves extend from the valve seat *h'* to the lower end of the throttle 20 valve and communicate with lateral passages *h*² which deliver to the stand pipe D. The nut *h*² is located a short distance below the bottom of the throttle valve when the drift valve is closed. When the drift valve 25 is raised it can move a short distance without moving the throttle valve. Thereafter if the drift valve is further raised, the nut *h*² comes in contact with the throttle valve so that a further movement of the drift valve 30 will raise the throttle valve to the desired extent.

The valve rod H is operated by an arm K detachably connected with the rod H at *k*¹⁰ and at its opposite end secured to a rock 35 shaft L, the inner end of which is mounted to turn in a bracket *l* secured to the upper part *a* of the dome. The outer end of the rock shaft carries a crank arm *m* which is connected with a rod M extending to the locomotive cab and operated by mechanism N of well known construction. The shaft L extends through a threaded sleeve O fitted in the side of the dome top and it is adapted to turn in said sleeve. P indicates a 45 packing gland which prevents leakage of steam around the shaft L.

By my improvements the pilot or drift valve may be operated without lifting the throttle valve. This pilot valve may thus 50 be used for starting the engine or may be used while drifting. Steam passes directly from the steam dome past the drift valve to the dry pipe, thus eliminating the pulling out of draw heads and the breaking up of 55 trains while drifting. The valve is made in two parts only, namely, the main throttle valve and the drift valve, and can be used either with or without the lower valve part *g*². While I have shown ports *e*² above the 60 valve seat *z* it will be understood that when desired these ports may be used in connection with other ports. Access can be had to the valve mechanism much more readily than heretofore since there are no parts to 65 be removed except the dome cap *a'*.

When it becomes necessary to grind the throttle valve seats, the dome cap may be removed and the crank K disconnected from the valve and valve G may be withdrawn, thereby exposing the seats *y*, *z* and *w* for 70 grinding.

The boiler may be entered by removing the dome cap *a'* only. The valve box, throttle valve and operating mechanism may be dismantled or replaced without the delay 75 that usually occurs with the throttle valve and rigging that is used on most locomotives in the present day. By removing the bolt *k*¹⁰ the arm K may be disconnected from the valve very quickly. 80

I claim as my invention:

1. The combination with the steam dome and stand pipe of a locomotive, of a throttle valve box connected with the stand pipe having seats for the throttle valve, a throttle 85 valve operating in the box and having a central bore connected at its lower end with the stand pipe, a drift valve having a limited vertical movement in the bore of the throttle valve for controlling the passage of 90 steam therethrough, and means for operating the drift valve.

2. The combination with the steam dome and stand pipe of a locomotive, of a throttle valve box connected with the stand pipe having 95 seats for the throttle valve, a throttle valve operating in the box and having a central bore connected at its lower end with the stand pipe, a drift valve having a limited vertical movement in the bore of the throttle 100 valve and controlling the passage of steam therethrough, and means for operating the drift valve and the throttle valve.

3. The combination with the steam dome and stand pipe of a locomotive, of a throttle 105 valve box connected with the stand pipe having seats for the throttle valve, a throttle valve operating in the box having a central bore connected at its lower end with the stand pipe, and having vertical grooves for conveying steam from the steam dome to the stand pipe, a drift valve having a limited vertical movement in the bore and controlling the passage of steam through said grooves from the steam dome to the stand pipe, and means 110 for operating said drift valve.

4. The combination with the steam dome and standpipe of a locomotive of a detachable cap for the dome, a throttle valve box supported on the standpipe within the dome, a throttle valve operating in the valve box, a rock shaft supported by the dome above the top of the throttle valve box, a crank arm rigidly secured to the rock shaft, and a detachable connection between said crank arm 120 and the upper portion of the throttle valve.

5. The combination with the steam dome and standpipe of a locomotive, of a cap for the dome, a throttle valve box on the standpipe within the dome, a throttle valve op- 125 130

erating in the valve box, a drift valve operating in the throttle valve, a rock shaft carried by the dome above the valve box and connected with the upper portion of the drift valve, and means for operating said rock shaft.

6. The combination with the steam dome and standpipe of a locomotive, of a cap for the dome, a valve box supported on the standpipe within the dome, a throttle valve operating in said box, a drift valve having a limited movement in the throttle valve, a rock shaft carried by the dome above the throttle valve and which is connected with the upper portion of the drift valve, a sleeve attached to the dome through which the rock shaft extends, packing for the sleeve and rock shaft attached to the dome, and means for operating the rock shaft.
- 10 7. The combination with the steam dome and stand pipe of a locomotive, of a throttle valve box supported by the stand pipe hav-

ing three valve seats arranged at different levels, a throttle valve operating in said box and having valve portions engaging said three seats, and means for operating said throttle valve.

8. The combination with the steam dome and standpipe of a locomotive of a throttle valve box detachably connected with the stand pipe and having a seat for the throttle valve, a throttle valve operating in the box and having a central bore passing entirely therethrough and communicating at its lower end with the stand pipe, a drift valve having a limited vertical movement in said bore for controlling the passage of steam therethrough, means for operating the drift valve, and means detachably connecting the upper end of the drift valve with the operating means.

In testimony whereof, I have hereunto subscribed my name.

HENRY CLAY RONEY.
